UNITED STATES PATENT OFFICE

148,945

DESIGN FOR A SUCTION CLEANER CASING

Joseph H. Nuffer, Toledo, Ohio, and Lynn H. Latta, Los Angeles, Calif., assignors to Air-Way Electric Appliance Corporation, Toledo, Ohio, a corporation of Delaware

Application October 21, 1946, Serial No. 134,146

Term of patent 7 years

(Cl. D9—2)

To all whom it may concern:

Be it known that we, Joseph H. Nuffer and Lynn H. Latta, citizens of the United States and residents of Toledo, Lucas County, Ohio, and Los Angeles, Los Angeles County, California, have invented a new, original, and ornamental Design for a Suction Cleaner Casing, of which the following is a specification, reference being had to the accompanying drawing, forming a part thereof.

In the drawing:

Fig. 1 is a top perspective view of a suction cleaner casing, showing our new design;

Fig. 2 is a top plan view;

Fig. 3 is a front end elevational view, and

Fig. 4 is a rear end elevational view thereof.
We claim:

The ornamental design for a suction cleaner casing, as shown.

JOSEPH H. NUSSER.
LYNN H. LATTA.
